UNITED STATES PATENT OFFICE

RUDOLPH A. HAEGG, OF ROCKFORD, ILLINOIS, ASSIGNOR TO BURD HIGH COMPRESSION RING COMPANY, OF ROCKFORD, ILLINOIS, A CORPORATION OF ILLINOIS

PISTON RING SNAGGING MACHINE

Application filed July 15, 1927. Serial No. 205,896.

This invention relates generally to grinding machines but has particular reference to a machine for snagging piston rings much more economically and expeditiously than was heretofore possible.

Cast piston rings cannot be machined before the very hard and brittle scale has been removed. This scale is usually ground off and in the past this operation has involved considerable expense as each ring had to be chucked for presentation to the grinder. I have found that the elimination of the chucking step greatly increases production, enables the use of relatively unskilled labor and, by reason of these facts, considerably reduces the manufacturing cost.

In the present case, the rings are simply fed into the grinding position in front of the grinding face and are engaged one by one by an improved means of my invention which serves to press the rings against the grinding face and simultaneously to rotate the same so that the peripheries of the rings are ground uniformly. The means comprises a pair of rollers mounted on a head movable toward and away from the grinder, the rollers being provided with gears meshing with a gear on a driven shaft journaled in the head for communicating rotation to both rollers in the same direction. The rings are gripped by the rollers in the mere act of moving the head toward the grinder and the rings are likewise released in the mere act of withdrawing the head. Thus, the chucking operation is dispensed with and it is unnecessary for the operator to pick up and handle each ring separately as was the case with the old method.

A special feature of the device of my invention lies in the universal adjustability thereof to accommodate various sized rings. The rollers which engage the piston rings peripherally are both mounted for adjustment on a radius to be brought farther apart or closer together accordingly as the rings to be snagged are larger or smaller in diameter.

The invention is illustrated in the accompanying drawings wherein—

50 Figure 1 is a front view of my machine,

only the important parts thereof being illustrated and the head being shown in section to disclose the roller drive;

Fig. 2 is a plan view of Fig. 1 with certain parts appearing in horizontal section in the plane of the line 2—2 of Fig. 1;

Fig. 3 is a plan view of a head of modified or alternative construction which enables adjustment of the rollers toward and away from one another to accommodate different sized rings; and

Fig. 4 is a central vertical section through Fig. 3.

The same or similar reference numerals are applied to corresponding parts throughout the views.

The machine comprises a work table or other suitable support 5 on the frame of the machine disposed in a horizontal position in front of the grinding face 6 provided on the grinding wheel 7. The latter is also carried on the frame of the machine and turns in the direction of the arrow appearing in Fig. 1 in a plane substantially at right angles to the work table 5. The table 5 has a stack of rings 8 received in a holder 9 at one end thereof. A reciprocable slide 10 enters beneath the stack to expel the lowermost ring to a position beneath a guide 11 and between guides 12 and 13. Thus, the rings are fed one by one to the grinding position at one end of the table and after the grinding operation are discharged down the incline 14 onto a rod or into a receptacle placed to receive the same. According to my invention a work holding device, indicated generally by the reference numeral 15, is provided at the grinding position for releasably engaging the rings one by one as they come into position, the said device being arranged to press the rings against the grinding face in the manner indicated in Fig. 2, and at the same time communicate rotation thereto as indicated by the arrow in the same figure, so that the entire periphery of the ring is ground to a uniform extent sufficient to remove the rough and very hard and brittle scale.

The device 15 comprises a pair of rollers 16, preferably of rubber, for friction drive

85

90

100

purposes, and arranged to engage the ring at circumferentially spaced points as shown. These rollers have the stems 17 thereof journaled in a housing member 18 which therefore constitutes a head or carrier arranged to be moved manually or otherwise. Pinions 19 are provided on the stem 17 within the housing 18 and mesh with a pinion 20 provided on a driven shaft 21 also journaled in the housing 18. The shaft 21, unless it has its driving means movable with the head, may be a flexible shaft to permit back and forth movement of the head relative to the driving means or may have a universal joint driving connection to permit of such operation. Obviously, the rollers 16 are driven in the same direction as indicated by the arrows in Fig. 2 when the shaft 21 is driven in the direction of the arrow shown in Fig. 1. Provision may be made for the automatic operation of the slide 10 forward in the retracting of the head so that as each ring is finished another ring is brought into position. The connections for accomplishing this operation are not illustrated inasmuch as the same might be of any suitable form.

It will be apparent from the foregoing that the present method of operation greatly facilitates the ring snagging operation by eliminating the necessity for the separate handling of each ring for chucking the same. Relatively unskilled labor may be employed for operating a machine made in accordance with my invention. An operator soon becomes quite proficient in the grinding of the rings according to the present simple method and will readily turn out a far greater number of properly snagged rings per day than could possibly be produced by the old method.

Referring to Figs. 3 and 4 wherein I have shown a device 15' of alternative or modified construction, it will be observed that the head 18' wherein the shaft 21 is journaled has the stems 17 of the rollers 16 supported thereby on arms 22 and 23 for adjustment in an arc with the shaft 21 as a center, as clearly indicated in dotted lines in Fig. 3. The adjustment of the arms 22 and 23 manifestly brings the rollers 16 closer together, as, for example, to accommodate a ring A of comparatively small diameter, or brings the rollers farther apart to accommodate a ring B of comparatively large diameter. In any position of adjustment of the arms 22 the pinions 19 remain meshed with the pinion 20 and provision is made for securing the arms in any position of adjustment, as indicated at 24, the means comprising set screws threading through the hubs of the arms 22 against the shank portion of the head 18' in relation to which the arms are swingable. It is a very simple matter to adjust the rollers to the proper position and to set the same in their adjusted position. For most practical pur-

poses the rollers 16 are set to engage the ring at points angularly displaced at from 90° to 120°.

I claim:

1. A piston ring snagging machine comprising, in combination, a work support, a rotary grinder turning in a plane approximately at right angles to the work support and having a side grinding face, said support being arranged to receive a piston ring laid flat thereon with the periphery thereof presented to said side grinding face, a guide over said work support serving to hold the piston ring flat on the support but permitting turning of said ring and means for simultaneously rotating the ring and pressing the periphery thereof against the grinding face comprising a pair of driven rollers adapted for engaging the periphery of the ring at circumferentially spaced points and to turn in the same direction approximately in the plane of the support and the ring thereon, said rollers being mounted on and movable bodily with a head whereby the same are arranged to be moved toward the grinder to press the ring against the same and communicate rotation thereto at the same time.

2. In a machine of the character described, a rotary grinder for cross grinding the periphery of rings or other circular pieces, a work support extending diametrically across the side grinding face of the grinder, means for holding a ring on said support in a fixed plane but permitting the turning thereof, and a work feeding and driving head movable toward and away from the side grinding face of the grinder to move the rings one by one toward the grinding face and press the same against said face for the cross grinding of the periphery thereof and simultaneously drive the same, said head having a pair of laterally spaced rollers for engaging the periphery of the ring at spaced points so that the ring is held therebetween against lateral movement out of grinding position, at least one of said rollers being driven, said head by virtue of the construction described being arranged by the mere act of movement toward the grinder to grip and drive the work while holding it from movement laterally and by the mere act of movement away from the grinder to release the same.

3. In a machine of the character described, a rotary grinder for cross grinding the periphery of rings or other circular pieces, a work support extending substantially diametrically across the side grinding face of the grinder, means for feeding rings over said support to one side of the grinder and means movable toward and away from the grinding face to press the rings one by one against the face for the cross grinding thereof, said means in addition to pressing the work against the grinder serving to rotate the same and being arranged by the mere act of move-

ment toward the grinder to grip the work and by the mere act of movement away from the grinder to release the same, said means comprising a pair of rollers rotatably mounted on a carrier movable toward and away from the grinder, said carrier having a driven shaft journaled therein, a gear on said shaft and gears meshing therewith mounted on the rollers whereby rotation is communicated in the same direction to both of said rollers.

4. In a machine of the character described a support arranged to receive a piston ring laid flat thereon, means for cross grinding the periphery of said ring when the same is pressed thereto, and a head having a pair of rollers mounted thereon arranged to bear against the periphery of the ring toward the grinding means to press the ring against the same, means for communicating rotation to at least one of the rollers, said rollers being mounted on arms swingable with reference to the head to bring the rollers closer together or farther apart, and means for securing the arms in adjusted position.

5. In a piston ring snagging machine adapted for snagging rings of different diameters, the combination with a work support, a grinder operating in a plane approximately at right angles to the work support and a guide over said support serving to hold a ring flat on the support while permitting turning thereof, of means for simultaneously turning the ring and pressing the same toward the grinder for cross-grinding of the periphery thereof, said means comprising a head movable toward and away from the grinder having a pair of rollers mounted thereon arranged to bear against the periphery of the ring toward the grinder to press the ring against the same, means for communicating rotation to at least one of the rollers whereby positively to turn the ring, said rollers being mounted on arms swingable with reference to the head to bring the rollers closer together or farther apart according to the diameter of the ring being snagged, and means for securing the arms in adjusted positions.

6. In a machine of the character described, a support arranged to receive a piston ring or the like laid flat thereon, means for cross grinding the periphery of said ring when the same is pressed thereto, and a head having a pair of rollers mounted thereon arranged to bear against the periphery of the ring at spaced points to press the ring against the grinding means and at the same time hold it against lateral movement out of grinding position, a center driving gear for communicating rotation to said rollers, said rollers being mounted on arms swingable with reference to the head about the gear center to bring the rollers closer together or farther apart, gears for driving the rollers meshing with the cen-

ter gear and arranged in the swinging of the arms from one position to another to keep the same meshing engagement with the center gear, and means for securing the arms in adjusted position.

7. In a machine of the character described, a support arranged to receive a piston ring or the like laid flat thereon, means for cross grinding the periphery of said ring when the same is pressed thereto, a work feeding and driving head movable toward and away from the grinding means, a driving shaft journaled therein, a center driving gear on said shaft driven thereby, a pair of arms having the inner ends thereof received on a bearing portion on said head concentric with the center gear, said arms being swingable with reference to the head to different positions, means for securing the arms to the head in adjusted position, rollers mounted for rotation on the outer ends of said arms and arranged in the adjustment of the arms to be brought closer together or farther apart and being arranged to bear against the periphery of a ring to be ground, and gears for driving said rollers carried therewith on the outer ends of said arms and meshing with the center gear in any position of adjustment of the arms.

8. In a machine of the character described adapted for peripherally grinding piston rings or the like, the combination with a grinder, of means for confining a ring in grinding position, turning the ring while so disposed, and pressing the turning ring into peripheral contact with the grinder at one point of the ring's periphery, said means including a pair of rollers engaging the ring at two points equally spaced circumferentially on either side of the point of contact, at least one of said rollers being driven to communicate drive to the ring by frictional contact with the periphery thereof, and a pair of separate supports for the rollers mounted for swinging movement to bring the rollers closer together or farther apart according to the outside diameter of the ring to be ground, whereby to maintain a predetermined ratio between the ring diameter and the spacing of the rollers said supports having means for securing the same in adjusted position to maintain the rollers in a predetermined desired spaced relation.

9. In a machine for peripherally grinding circular work pieces such as piston rings, the combination with a grinder, of a pair of spaced drive rollers arranged to engage the circular work piece at two points circumferentially spaced to either side of the point where the work piece engages the surface of the grinder, means for driving one or both rollers so they turn in the same direction and at the same peripheral speed whereby to turn the work piece relative to the surface of the grinder for the complete peripheral grind-

ing thereof, and a member arranged to be moved to bring the work piece and rollers into operative relation to one another whereby to cause the work piece to turn, said member being further arranged to press the work piece toward the grinder while it is rotating, whereby to determine the extent of the grinding action.

10. In a machine for peripherally grinding circular work pieces such as piston rings, the combination with a grinder, of a pair of spaced drive rollers arranged for engagement with the periphery of the work piece at two points spaced circumferentially thereof, said rollers being of compressible resilient material, such as rubber, whereby to afford a good frictional driving connection between the rollers and the work piece when the parts are pressed together, means 15 for driving one or both rollers so they turn in the same direction and at the same peripheral speed whereby to turn the work piece relative to the grinder for the complete peripheral grinding thereof, and a member 20 movable toward and away from the grinder to press and release a work piece with relation thereto, said device being arranged in its forward movement to first bring the work piece and rollers into drive transmitting relation so as to insure turning of the work 25 piece prior to its engagement with the grinder, and said member being arranged in its further movement forwardly to press the work piece against the grinder with a predetermined pressure to effect a predetermined desired grinding action, the said rollers being at the same time compressed where 30 they engage the work piece whereby to afford the required good frictional drive for the work piece.

11. In a machine for peripherally grinding circular work pieces such as piston rings, the combination with a grinder, of a member movable forwardly and rearwardly with reference to the grinder to press and release a work piece placed between the member and the grinder, a pair of drive rollers spaced for engagement with the periphery of the work piece at two circumferentially spaced points thereon, said rollers being disposed in a plane substantially at right angles to the path of movement of the aforesaid member and approximately equally spaced to either side of the point where the work piece engages the grinder, whereby in the forward movement of the member the said rollers come into engagement with the work piece substantially simultaneously, and whereby 55 in the further forward movement of said member to press the work piece into engagement with the grinder, the said rollers exert substantially the same pressure against the work piece, and means for driving one or both rollers so they turn in the same di-

rection and at substantially the same peripheral speed.

12. In a machine for grinding circular work pieces such as piston rings on one of the circumferences thereof, the combination with fixed and relatively movable supports, of a grinder on one of said supports arranged to engage a work piece at one point on the circumference to be ground, a pair of spaced drive rollers carried on the other support arranged to engage the work piece at two points circumferentially spaced to either side of the point where the work piece engages the surface of the grinder, said rollers being of compressible resilient material, such as rubber, whereby to afford a good frictional driving connection between the rollers and the work piece when the parts are pressed together, means for driving one or both rollers so they turn in the same direction and at the same peripheral speed whereby to turn the work piece relative to the surface of the grinder, and means for moving the movable support to bring the work piece and rollers into operative relation to one another, whereby to cause the work piece to turn, and to exert pressure between the work piece and grinder during the turning of the work piece, whereby to determine the extent of the grinding action, the said rollers being at the same time compressed where they engage the work piece whereby to afford the required good frictional drive for the work piece.

In witness of the foregoing I affix my signature.

RUDOLPH A. HAEGG.
